UNITED STATES PATENT OFFICE.

HAROLD W. EDEN, OF CHICAGO, ILLINOIS.

CLOTHES-DRUM CONSTRUCTION.

1,169,782.

Specification of Letters Patent. Patented Feb. 1, 1916.

Application filed January 26, 1914. Serial No. 814,414.

To all whom it may concern:

Be it known that I, HAROLD W. EDEN, a citizen of the United States, and a resident of the city of Chicago, in the county of Cook and State of Illinois, have invented certain new and useful Improvements in Clothes-Drum Construction; and I do hereby declare that the following is a full, clear, and exact description of the same, reference being had to the accompanying drawings, and to the numerals of reference marked thereon, which form a part of this specification.

This invention relates to a clothes drum for washing machines wherein a foraminous material forms the outer wall of the drum and is suitably braced thereon by ribs which project radially into the drum for the purpose of lifting the clothes when the drum is rotated.

It is an object of this invention to construct a device wherein a plurality of ribs extend longitudinally within the clothes drum for the purpose of lifting the clothes thereupon during rotation of the drum.

It is also an object of this invention to provide a clothes drum having outwardly dished metallic ends to which are attached ribs connecting the same, and wound thereabout with a material permitting a free flow

of water in and through the drum. It is also an object of this invention to provide a clothes drum having outwardly dished sheet metal ends provided with an out-turned flange, and with ribs connecting said ends to one another and having a covering of screen like material secured thereon and over said flanges.

It is furthermore an object of this invention to provide a clothes drum wherein no central supporting shaft extends therethrough to impede the movement of clothes within the same.

It is finally an object of this invention to construct a clothes drum consisting of few parts securely connected together affording a light and durable construction and with no projections therein likely to tear the clothes.

The invention (in a preferred form) is more fully described and defined in the accompanying drawings and specification.

In the drawings: Figure 1, is a central vertical section of a washing machine provided with a drum embodying the principles of my invention. Fig. 2 is an enlarged view partly broken away of a clothes drum. Fig.

3 is a transverse section therethrough on the line 3—3, Fig. 2. Fig. 4 is an enlarged fragmentary detail showing in section the relation of the assembled elements at one of the metallic ends thereof. Fig. 5 is an enlarged detail illustrating a latching means for doors provided upon the clothes drum.

As shown in the drawings: A conventional type of washing machine is indicated as a whole by the reference numeral 1, with drive gearing 2, mounted on one side thereof and a wringer 3, conveniently disposed at one side and at the top thereof. A clothes drum is adapted to rotate therein driven by said gear and comprises outwardly dished metallic ends 4, and 5, respectively. A spider 6, is secured on said end 4, and affords a gudgeon shaft 7, adapted to be supported in suitable bearings on the washing machine. A socket 8, is secured on the other end of said drum and is adapted to receive therein the squared end of a driving shaft from said gearing 2, though not shown. Secured to each of said metallic ends 4, and 5, are longitudinal ribs 10, preferably constructed of wood which not only serve to maintain the ends in proper spaced relation from one another but also serve to sustain a foraminous material 11, which forms the side walls of said drum, properly disposed thereabout. For the purpose of further securing the screen like material 11, on the device the periphery of each of said ends is flanged outwardly as indicated by the reference numeral 12, and the margin 13, of said screening 11, is turned over and beneath said flange. Retaining battens 14, are secured on the outer side of the screening 11, directly over the ribs 10, and are secured to said ribs by means of nails or pins 15.

At one side of the device are provided ribs 16, similar to, though of slightly less width than said ribs 10, and hingedly mounted on the outer side thereof are doors 17, and 18, respectively, the latter of which is of slightly greater width than the former and overlaps the same when the two are closed. Said doors are likewise constructed of screen like material, and the outer edges thereof affording the hinges are bound with metallic sheeting 19. Similar sheeting 20 covering the terminating ends of said screening 11, forming the walls of the drum serve, in connection with the pieces 19, as the hinges. For the purpose of retaining said door 18, in closed position a latch 21, is

hingedly mounted on the under side of said extended flange portion 12, and projects upwardly and is adapted to close over the end of said door, one of said latches being provided on each end of the drum. When said clothes drum is in use the doors 17, and 18, are closed with the clothes contained within and the drum is rotated submerged, or partially submerged in a tub suitably constructed for the purpose and forming a part of the washing machine. Of course, with continued rotation of the drum the water rushes in and out of the apertures in the screen like foraminous material 11, thoroughly washing the clothes contained within the drum.

I am aware that the details of construction may be varied through a wide range without departing from the principles of this invention. I therefore do not purpose lim-

iting the patent granted otherwise than necessitated by the prior art.

I claim as my invention:

In a device of the class described, metallic ends having out-turned flanges thereon, ribs connecting said ends, foraminous material secured on the margin of said flanges and extending around said ribs affording a cylinder and having its edges turned over and beneath said flanges, and retaining battens on the outer surface of said foraminous material secured to the same and to said ribs and overlying said flanges. 25 30 35

In testimony whereof I have hereunto subscribed my name in the presence of two subscribing witnesses.

HAROLD W. EDEN.
